UNITED STATES PATENT OFFICE.

ROBERT H. WENTORF AND ERNEST A. KERLER, OF WEST BEND, WISCONSIN, ASSIGNEES TO WEST BEND ALUMINUM COMPANY, A CORPORATION OF WISCONSIN.

DETACHABLE COVER FOR WATERLESS COOKERS.

Application filed August 24, 1923. Serial No. 659,048.

To all whom it may concern:

Be it known that we, ROBERT H. WENTORF and ERNEST A. KERLER, both citizens of the United States, residing at West Bend, in the county of Washington and State of Wisconsin, have invented certain new and useful Improvements in Detachable Covers for Waterless Cookers, of which the following is a specification.

This invention relates to cooking vessels and is more particularly directed to a detachable cover for a class of cooking vessels better known as waterless boilers, and has for its primary object the provision of locking means for preventing the cover of the boiler from being forced therefrom by the pressure of steam within the boiler.

A further object of the invention is to provide a device which will automatically lock the cover to the boiler when the cover is properly seated on the top of the boiler.

A still further object of the invention is to provide a quick, detachable cover and one which can be secured to the boiler so as to be substantially steam tight.

These and other objects are obtained by providing a plurality of pivoted latch members mounted on the cover and adapted to co-operate with the boiler when the cover is positioned on the same to automatically lock the cover to the boiler so as to be steam tight.

Referring to the drawings, Fig. 1 is a side elevational view partly in section of a boiler and cover showing my improved locking means mounted thereon.

Fig. 2 is an enlarged fragmentary top plan view showing the manner in which the latch members are pivotally secured to the cover, and

Fig. 3 is an enlarged perspective view of our improved gravity actuated latch member.

The invention hereinafter described and claimed is an improvement over co-pending application Serial No. 592,279 of Robert H. Wentorf and Ernest A. Kerler filed October 4, 1922.

For purposes of illustration we have shown our improved locking means for detachably securing a cover to a boiler 5, which is preferably of the waterless type of boiler. The boiler 5 is provided with the usual base 6 and usual bead 7 formed at the top thereof for strengthening and reinforcing

ing the boiler construction. In the present invention the bead is rolled outwardly from the wall of the boiler, as clearly shown in the cross sectional view of Fig. 1. Detachably seated on the top of boiler 5 is a cover member 8 of dome-like construction. This cover is provided with a peripherally arranged bead, as shown at 9, the diameter of this knurl being of greater diameter than that of the boiler proper. Extending downwardly from the peripherally arranged knurl 9 with a gradual taper therefrom is a telescoping portion 10 which is adapted for telescopic connection with the top of the boiler. The cover 8 is provided with 70 looplike handles 11 secured to the cover by means of rivets 12. The outer ends of the handles 11 extend outwardly, as shown at 13, so as to form pivotal supports 14 for our improved locking means. Our improved automatically actuated locking device comprises latching members 15, which are formed of substantially a flat piece of metal having a tongue 16 depressed inwardly from the latch member at a point 80 substantially centrally of the same. Formed on the upper end of the latch member 15 and integrally therewith are two oppositely positioned bearing portions 17 which are adapted to receive a pin 18 in 85 pivotally supporting the latch member 15 to the pivotal support 14 of the handles 11. It will be noted that the latch members 15 are so constructed that they normally assume a position slightly inwardly from the 90 vertical position, because the pivots 17 of these members are slightly offset with respect to the plane of the body portion of these members. It will also be noted that the tongues 16 of these latch members 15 95 are inclined upwardly and inwardly at substantially an angle of 45 degrees. By reason of this inclined construction, the tongues 16 have a camming action against the bead 7 of the top of the boiler and 100 cause these latch members to swing outwardly with respect to the cover as the telescoping portion 10 of the cover 8 is depressed in the top of the boiler, and as soon as the cover is properly seated or depressed to its normal steam-tight position, the latches 15 are actuated by gravity to their normal vertical positions or the positions shown in Fig. 1, wherein the upper or top 105 edges of the tongues 16 engage the under- 110

side of the bead 7 and firmly secure the cover to the boiler.

While in the above construction we have only shown two of these latches, employed, it will, of course, be understood that more than two may be employed, and preferably four are used in such a manner that they are spaced substantially at 90 degrees around the periphery of the cover so that a steam 10 tight connection between the cover and the boiler can always be assured.

In detaching the cover from the boiler, it will be readily seen that each of these latch members 15 may be readily actuated 15 or swung outwardly about their pivots, so that the upper edge of the tongues 16 of these latch members may be quickly disengaged from the bead 7 of the boiler 5 and the cover readily removed.

20 In the above specification, we have described one embodiment which our invention may assume in practice, but it will, of course, be understood that the same is capable of modification and that modification 25 may be made without departing from the spirit and scope of the invention, as expressed in the following claims.

What we claim as our invention and desire to secure by Letters Patent is:

30 1. A detachable cover for a vessel, comprising a cover member, and gravity actuated latches made of substantially flat material carried by said cover and depressed tongues formed substantially centrally of

said latches for detachably securing the 35 cover member to a vessel.

2. A detachable cover for a vessel comprising a cover member, gravity actuated latches made of substantially flat material pivoted on said cover, and depressed tongues formed substantially centrally of and extending upwardly at an angle with respect to said latches and adapted to engage said vessel for detachably 40 securing the cover member to said vessel. 45

3. A locking device for a boiler having a cover therefor, a bead around the top thereof, and a plurality of latches made of substantially flat material pivoted on said cover having upwardly and inwardly 50 inclined depressed tongues formed integrally therewith and normally actuated by gravity to engage the underside of said bead for securing the cover to said boiler.

4. A locking device for a boiler having 55 a cover therefor, a bead around the top thereof, a plurality of handles for said cover having their outer ends extending to the periphery of said cover, a plurality of latches pivoted at the outer ends of said 60 handles and depressed tongues formed integrally with said latches and engageable with said bead for securing said cover to said boiler.

In testimony whereof we have signed our 65 names to this specification.

ROBERT H. WENTORF.
ERNEST A. KERLER.
